R.F. TRANSFORMER DESIGN FOR MINIMUM COUPLING TO SHIELDING COVER

Henri T. Pichal, St. Petersburg, Fla., assignor to General Dynamics Corporation, Rochester, N.Y., a corporation of Delaware

Filed May 23, 1960, Ser. No. 30,917
12 Claims. (Cl. 336—87)

The present invention relates generally to a new and improved high frequency transformer assembly and is more particularly concerned with a small, compact transformer assembly including an outer housing for magnetic and electrostatic shielding but constructed and arranged to minimize losses in order to provide high Q.

Bandpass transformers or coupled circuits are generally constructed with both windings wound on a single coil form usually cylindrical in shape so that the two windings are coaxial. In order to provide both electrostatic and magnetic shielding these windings are enclosed within a metal box or can which may be either cylindrical or rectangular in shape. If the shielding can is approximately the same size as the windings, substantial losses are introduced as a result of the coupling between the shielding can and the windings. Therefore, when a high Q transformer is desired, the shielding can is presently made relatively large in order to reduce this coupling. At low radio frequencies, ferrite coil forms or potted assemblies are used to increase Q by concentrating the mutual flux linkages between the windings and reducing the leakage flux through the shielding can. However, at higher radio frequencies, for example, about 30 megacycles and above, the advantages of the ferrite coil forms begin to diminish until at about 40 to 50 megacycles higher Q values are obtained by using air core inductances. Thus, with a shielding can of given dimensions, the attainable Q has a fixed ceiling beyond which no improvement can be made without the use of external circuit aids. Moreover, the space limitations of the equipment in which the transformer is to be used generally prevent increase of the size of the shielding can to improve the Q. Thus, shielded transformers are usually designed to provide a compromise between the size of the shielding can and the Q. It would, of course, be desirable to provide a transformer assembly having a Q very near the optimum value, i.e., the value which can be obtained without a shielding can, while at the same time using a shielding can of small size and the satisfaction of this desire, therefore, constitutes one of the primary objects of the present invention.

A further object of the invention is to provide a high Q transformer shielded electrostatically and magnetically but also free from radiation to external circuits, thereby making this transformer especially well suited for use in coupling between stages in an amplifier chain.

The invention has for another object the provision of a high Q transformer having a pair of windings mounted within a shielding can for adjustment with respect to each other in order to alter the coupling therebetween with the adjusting mechanism being covered or shielded to prevent radiation of signals to circuits external to the shielding can.

The foregoing and other objects are realized in accordance with the present invention, by providing a transformer wherein the primary and secondary windings are wound with their respective axes parallel to one another. The shielding can takes the form of a relatively flat, rectangularly shaped can which provides a long loop coupling to the transformer windings, thereby reducing the losses due to leakage flux. A slot is provided along one of the sides of the can for the purpose of further reducing the coupling between windings caused by the presence of the can. To retain the benefits of magnetic shielding

2

by the can the slot is so formed that the magnetic loop axis is parallel to both windings, a result which is accomplished by forming the slot longitudinally along one side of the can and extending at right angles to the winding axes of the coils. The described construction retains slight coupling between the enclosed windings and at the same time conserves the high Q values of these windings. Provision is also made for adjusting the windings with respect to each other to vary the coupling. The assembly is completed by a detachable shielding clip which covers the adjusting mechanism and embraces the can. This clip may be removed to permit the coupling adjustment but, when in position, it serves to eliminate radiation from the enclosed windings to the circuits external to the can, thus making the coupling transformer of this invention very well suited for use in coupling a series of amplifying stages.

The invention, both as to its organization and manner of operation, together with further objects and advantages, will best be understood by reference to the following description taken in conjunction with the accompanying drawing wherein:

FIG. 1 is a perspective view illustrating an RF transformer assembly characterized by the features of the present invention;

FIG. 2 is an enlarged sectional view taken along a line substantially corresponding to the line 2—2 of FIG. 1;

FIG. 3 is a sectional view taken along a line corresponding substantially to the line 3—3 in FIG. 2 assuming, of course, that the latter shows the entire transformer assembly; and

FIG. 4 is a fragmentary, exploded, perspective view illustrating particularly an adjustable mounting arrangement for one of the windings of the transformer assembly shown in FIGS. 1 to 3.

Referring now to the drawing, a transformer assembly characterized by the features of the present invention is there identified generally by the reference numeral 10 and includes a pair of windings 11 and 12 one of which serves as the primary winding of the transformer and the other of which serves as the secondary winding. It will be recognized that either one of the windings 11 or 12 may be used as the primary winding. Each of the windings 11 and 12 includes a coil formed of a number of turns wound upon an appropriate coil form of low-loss dielectric or insulating material preferably cylindrical in shape. The coil form for the winding 11 is identified by the reference numeral 13 while that for the winding 12 is indicated by the numeral 14. The coil forms 13 and 14 are supported in spaced apart positions upon a shielding can 15 with their winding axes extending parallel to each other.

To support the winding 12, the two ends of the coil form 14 are respectively glued or otherwise secured to the side walls 16 and 17 of the can as indicated at 18 and 19. The coil form 14 may include an annular collar or flange 24 seating against the side wall 16 and formed adjacent an outer end 20 which extends through an opening in the wall 16 to permit access from the exterior of the shielding can so that a core 22 may be adjustably threaded into or out of the coil form. The winding 11 may also be secured in fixed position by gluing its ends to the sides of the shielding can. However, in cases where it is desired to provide for varying the coupling between the windings 11 and 12, the coil form 13 is mounted for adjustment vertically upon the shielding can 15. To this end, the side wall 16 is provided with an elongated opening 26 for accommodating one end 28 of the coil form 13. The end 28 of the coil form 13 includes an externally threaded portion 30 protruding beyond the wall 16 to receive a nut 31 which may be tightened to lock the coil form 13 in position. An annular collar 35 on the coil

form 13 seats against the side wall 16 so that when the nut 31 is tightened, the coil form 13 is clamped to the side wall 16 to provide a cantilever type support. The nut 31, when loosened, permits vertical adjustment of the position of the winding 11 by moving the coil form within the opening 26. The winding 11 is lowered as viewed in FIG. 2 to increase the coupling between the primary and secondary windings and is raised to decrease the coupling. To prevent the coil form 13 from turning about its axis the end portion 28, as is best shown in FIGS. 3 and 4, includes a flange 32 having diametrically opposed flat portions 33 and 34 thereon lying contiguous to the opposed side edges of the slot 26.

The shielding can 15, of course, is formed of conducting metal to provide the aforementioned electrostatic and magnetic shielding. In accordance with an important feature of the present invention, the shielding can be made very small without adversely affecting the Q of the transformer to any great degree. Specifically, the width of the can may be made approximately equal to the length of the coil forms 13 and 14 and the depth or thickness of the can may be made only slightly larger than the diameter of the windings 11 and 12. This desirable result may be attributed to the fact that since the height or longitudinal length of the shielding can is relatively long a relatively long loop coupling is provided to the transformer windings and, hence, the shielding can has little effect on the transformer Q. Thus, in one construction which has been found to provide satisfactory results windings having a diameter of 0.25 inch were used in a shielding can having an inside depth of only 0.32 inch and the resultant reduction in Q; that is, the Q of the transformer without any shielding as compared with the transformer Q obtained with the shielding can; was found to be only about 5%. The lengths of the coil forms 13 and 14 are at least 1.5 times the length of the coil windings thereon in order to minimize coupling into the side walls 16 and 17 of the shielding can.

In accordance with another very important feature of the invention, the side wall 16 of the shielding can 15 has a narrow slot 38 cut therethrough and extending from a point near the top of the can to a point near the bottom. This slot removes coupling between the windings 11 and 12 induced by the presence of the shielding can 15. In order to retain the benefits of magnetic shielding by the can 15, the shielding can is so shaped and the windings 11 and 12 are so oriented that the magnetic shielding loop has its axis extending parallel to the axes of all of the windings. This means that the slot 38 should extend longitudinally of the shielding can and at right angles to the axes of the windings 11 and 12, i.e., along one of the side walls as illustrated in the drawing. The described construction yields a maximum magnetic shielding for a minimum amount of coupling between the shielding can and the windings for a given volume. Thus, the windings may be assembled within a very small space while at the same time retaining loose coupling therebetween and also maintaining high Q values. The use of a slot in the shielding can in the manner described permits the coupling factor between the windings to be maintained at a low value even though the shielding can itself is relatively small.

The winding 11 may be of the type employing an adjustable core indicated at 40 in FIG. 2. The core 40 may be adjusted by inserting an insulated screw driver or other adjusting tool through the end of the coil form 13 which extends through the opening 26 in the side wall 16 of the shielding can. Without the presence of the holes 21 and 26 in the side wall 16, capacitors would be formed between the adjustable cores of the windings and the shielding can. These capacitors would provide undesired coupling into the side walls of the can. The holes in the end walls form a shorted turn for eddy currents caused by the magnetic flux induced in the shielding can and, hence, they cause an absorption of energy. Since the opening 26 breaks the magnetic path in the same manner as the

elongated slot 38 it may be desirable in some constructions to eliminate the elongated slot. However, the elongated slot has the advantage of breaking the short circuit around the openings and, hence, reduces the eddy currents described above. The use of the wide opening 26 opens the shielding effect of the can 15 and permits magnetic leakage therethrough. To avoid this magnetic leakage while at the same time retaining the aforementioned reduction in eddy currents, a metal clip or bridge 42 is placed over the opening 26. This clip includes a central web portion 43 having two integral arms 44 and 45, respectively, extending along the two side walls of the shielding can 15. The clip is dimensioned so that the arms 44 and 45 tightly embrace the can to prevent slipping and to provide low resistance electrical contact but the clip may be readily removed to permit adjustment of the core 40 or to alter the position of the winding 11 to adjust the coupling. If the clip tends to slip along the shielding can as may be caused, for example, by vibration, this clip may be soldered or spot welded very lightly without effectively bridging the slot or opening 26. An insulating layer 46 such as an insulating tape is secured to the inside of the central web 43 of the clip to prevent electrical contact and to avoid the introduction of excessive capacity between the clip and the core 40. Since the clip effectively prevents radiation of the transformer signals, its use is particularly effective when the transformer 10 is employed to provide coupling between stages in a series of amplifiers.

In view of the foregoing discussion, it will be recognized that the transformer assembly described may be made in a very small unit with the front and rear walls of the shielding can lying very close to the coils or windings while, at the same time, retaining the electrical characteristics of a high Q transformer. Thus, the assembly is best suited for use in installations where miniaturization of components is the prime concern. It will also be recognized that the use of a high Q transformer permits a given selectivity or bandpass to be realized without using a large number of stages and without delicate adjustments. Thus, the use of the transformer of the present invention results in a reduction in cost of component elements and at the same time increases the stability and reliability of the circuits in which it is employed.

While the present invention has been shown and described in conjunction with an illustrative embodiment thereof, many modifications will occur to those skilled in this art, and it is, therefore, contemplated by the appended claims to cover any such modifications as fall within the true spirit and scope of the invention.

What is claimed as new and desired to be secured by Letters Patent of the United States is:

1. A coupling transformer comprising an elongated shielding can of substantially rectangular cross section, said shielding can having a width between two side walls considerably greater than the depth between the front and rear walls and having a height from top to bottom considerably greater than the width, a primary winding and a secondary winding extending parallel to each other within said can, each of said windings being wound upon a dielectric coil form of cylindrical shape supported within the can with the two coil forms having substantially the same diameter, each of said coil forms extending between said side walls and being substantially co-extensive with the width of the can, each winding being wound about its coil form for a distance less than the length of the form so that both ends of each winding are spaced from the side walls of the can, the depth of the shielding can being only slightly greater than the diameter of the coil forms, and an elongated slot extending lengthwise along one of the side walls of said can to minimize the coupling between the windings and the can, thereby providing a high Q coupling transformer of very small size.

2. The apparatus defined by claim 1 wherein the elongated slot receives an end portion of one of said coil

forms and wherein releasable means are provided for clamping said one coil form in position, said one coil form being movable within the elongated slot when the releasable means is released in order to permit adjustment of the coupling between the windings.

3. The apparatus defined by claim 1 wherein each of the coil forms carries an adjustable core and wherein said one side wall of the can is provided with at least one opening to permit access to the adjustable cores by an adjusting tool.

4. Apparatus according to claim 3 wherein said one side wall is provided with a pair of spaced apart openings, one for each of said coil forms, and said elongated slot extends along said one side wall and intersects both of said openings.

5. Apparatus according to claim 1 wherein a conducting clip is placed over said shielding can to cover at least a portion of said one side wall, said clip including arms respectively engaging the front and rear walls of the can and being electrically insulated from said one side wall.

6. Apparatus according to claim 2 wherein a conducting clip is placed over said shielding can to cover the portion of said one side wall adjacent said slot, said clip including arms respectively engaging the front and rear walls of the can and being electrically insulated from said one side wall.

7. A coupling transformer comprising an elongated shielding can of substantially rectangular cross section, said shielding can having a width between two side walls considerably greater than the depth between the front and rear walls and having a height from top to bottom considerably greater than the width, a primary winding and a secondary winding extending parallel to each other within said can, each of said windings being wound upon a dielectric coil form supported within the can, each of said coil forms extending between said side walls and being substantially coextensive with the width of the can, each winding being wound about its coil form for a distance less than the length of the form so that both ends of each winding are spaced from the side walls of the can, the depth of the shielding can being only slightly

greater than the maximum transverse dimension of the coil forms, and an elongated slot extending lengthwise along one of the side walls of said can and perpendicular to the axes of the windings in order to minimize the coupling between the windings and the can, thereby providing a high Q coupling transformer of very small size.

8. The apparatus defined by claim 7 wherein the elongated slot receives an end portion of one of said coil forms and wherein releasable means are provided for clamping said one coil form in position, said one coil form being movable within the elongated slot when the releasable means is released in order to permit adjustment of the coupling between the windings.

9. The apparatus defined by claim 7 wherein each of the coil forms carries an adjustable core and wherein said one side wall of the can is provided with at least one opening to permit access to the adjustable cores by an adjusting tool.

10. Apparatus according to claim 9 wherein said one side wall is provided with a pair of spaced apart openings, one for each of said coil forms, and said elongated slot extends along said one side wall and intersects both of said openings.

11. Apparatus according to claim 7 wherein a conducting clip is placed over said shielding can to cover at least a portion of said one side wall, said clip including arms respectively engaging the front and rear walls of the can and being electrically insulated from said one side wall.

12. Apparatus according to claim 8 wherein a conducting clip is placed over said shielding can to cover the portion of said one side wall adjacent said slot, said clip including arms respectively engaging the front and rear walls of the can and being electrically insulated from said one side wall.
